United States Patent Office

Des. 214,779

Patented July 29, 1969

214,779

HINGE

George C. Sloan, Rte. 1, Box 323J,
Big Spring, Tex. 79720

Filed Apr. 11, 1968, Ser. No. 11,414

Term of patent 14 years

Int. Cl. D8—03

U.S. Cl. D8—189

The figure is a perspective view of a hinge, showing my new design.

The back of the hinge is planar and unornamented.

I claim:

The ornamental design for a hinge, as shown and described.
